Paul Tuttle, Los Angeles, Calif., assignor to Modern Color, Inc., Los Angeles, Calif., a corporation of California

Application March 24, 1952, Serial No. 19,024

Term of patent 14 years

(Cl. D15—8)

To all whom it may concern:

Be it known that I, Paul Tuttle, a citizen of the United States and a resident of the city of Los Angeles, in the county of Los Angeles and State of California, have invented a new, original, and ornamental Design for a Stool, of which the following is a specification, reference being had to the accompanying drawing, forming part thereof, in which:

Fig. 1 is a perspective view of a stool showing my new design;

Fig. 2 is a plan view; and

Fig. 3 is a side view.

I claim:

The ornamental design for a stool, as shown.

PAUL TUTTLE.
